UNITED STATES PATENT OFFICE.

JOHN NEARY, OF KOKOMO, INDIANA, ASSIGNOR TO KOKOMO RUBBER COMPANY, OF KOKOMO, INDIANA, A CORPORATION OF INDIANA.

DESIGN FOR A TIRE.

45,766.

Specification for Design.

Patented May 12, 1914.

Application filed February 27, 1914. Serial No. 821,584. Term of patent 7 years.

To all whom it may concern:

Be it known that I, JOHN NEARY, a citizen of the United States, residing at Kokomo, in the county of Howard, State of Indiana, have invented a new, original, and ornamental Design for a Tire, of which the following is a specification, reference being had to the accompanying drawings, forming a part thereof.

In the drawing, Figure 1 is a top plan view of the tread and Fig. 2 is a transverse sectional view on the line 2—2 of Fig. 1.

I claim:

The ornamental design for a tire, as shown.
JOHN NEARY.
